CLAIM

The ornamental design for a contoured handle, as shown and described.

DESCRIPTION

FIG. 1 is a top perspective view of a contoured handle for a tote;

FIG. 2 is an enlarged bottom perspective view of the contoured handle of FIG. 1;

FIG. 3 is a top plan view thereof;

FIG. 4 is a bottom plan view thereof;

FIG. 5 is a right side elevational view thereof;

FIG. 6 is a left side elevational view thereof; and,

FIG. 7 is a front elevational view thereof.

A rear elevational view is not shown because it is a mirror image of the front elevational view shown in FIG. 7.

The broken lines shown in FIG. 1 depict environmental subject matter only and form no part of the claimed design.
